WILLIAM BIRRELL AND JAMES BIRRELL, OF SEATTLE, WASHINGTON, ASSIGNEES TO
FRANK J. KOLMAN, TRUSTEE, OF SEATTLE, WASHINGTON.

VACUUM-PRODUCING DEVICE.

1,073,467.

Specification of Letters Patent. Patented Sept. 16, 1913.

Application filed March 18, 1912. Serial No. 684,595.

To all whom it may concern:

Be it known that we, WILLIAM BIRRELL and JAMES BIRRELL, citizens of the United States, residing at Seattle, in the county of 5 King and State of Washington, have invented certain new and useful Improvements in Vacuum-Producing Devices, of which the following is a specification.

This invention relates to vacuum producing appliances of the ejector type, and is designed to provide an efficient device of this character which is adapted to be attached to a water faucet and which will operate with comparatively little noise.

15 With these and other objects in view, the invention consists in the novel construction and combination of parts, as will be herein-after described and claimed.

The accompanying drawing is a vertical 20 sectional view of a vacuum producing device constructed and arranged in accordance with the present invention.

The shell or body 2 of the device is provided medially of its height with a conduit 25 3 which communicates with chambers 4 and 5 of greater diameters than the conduit and located at the top and bottom of the body.

6 represents a rubber thimble to receive the bib of a household faucet. Said thimble 30 is provided with a peripheral flange 6' which serves as a gasket to make an airtight joint between said body and a gland-nut 8 which engages screw threads provided on the body.

35 Extending from the chamber 4 and axially into said conduit is a nozzle 9. At a distance below the latter is an air inlet 10 extending through a nipple 11 which is adapted to be coupled with a hose 12 where-through the air is sucked into the device 40 when operating.

13 is a deflector or partition positioned within the chamber 5 and is of a conical shape with its apex protruding, desirably, 45 into the mouth of the conduit. Said partition has a serrated periphery affording apertures 14 in juxtaposition to the circular wall of the chamber, or at the bottom of a gutter 15 formed between such wall and the conical

partition. The partition, as illustrated in 50 the view, is secured by being pressed into the chamber 5 though it may be otherwise secured, if desired.

When the faucet is opened water fills the chamber 4 and is discharged through the 55 nozzle 9 against the apex of the partition 13 and is thereby deflected into gutter 15 and against the peripheral wall of the chamber 5. From this gutter the water escapes by falling through the holes 14 accompanied by 60 air whence a partial vacuum is created within the conduit 3 to induce a suction in the tube 12.

Advantages of the present vacuum producer reside in the fact that the water which 65 performs the work of the device is discharged unaccompanied by noise and that the air is exhausted with an economical consumption of water.

What we claim, is—

70 1. An aspirator comprising a conduit provided with a flaring mouth, a walled chamber of greater diameter than the conduit located therebelow and provided with a top substantially at right angles to its axis, a 75 sharp pointed conical deflector serrated at its lower edge and frictionally engaging the side walls of the walled chamber to prevent displacement thereof and provide a restricted water passage and having its apex 80 disposed within the flaring mouth.

2. An aspirator comprising a casing having a reduced medial portion provided with a lateral opening and enlarged cup-shaped ends, a sharp pointed conical deflector serrated at its lower edge adapted to be mounted in the lower end of the casing and held therein by frictional contact and having its apex extending into the lower end of the reduced medial portion.

85 90 Signed at Seattle, Wash., this 12th day of March, 1912.

WILLIAM BIRRELL.
JAMES BIRRELL.
